HEATING DEVICE

Richard H. Jordan, Springfield, Mass., assignor
to Westinghouse Electric & Manufacturing
Company, East Pittsburgh, Pa., a corporation
of Pennsylvania

Application February 21, 1934, Serial No. 712,349

6 Claims. (Cl. 219—39)

My invention relates to electrical heating devices and it has particular relation to electric hand driers and other comparable devices which produce a stream of heated air for direction 5 against objects which are to be dried.

In order to eliminate the necessity for towels in business office, public, and other washrooms, there have, in recent years, been developed mechanical driers which typically comprise an electric heater through which a motor-driven blower 10 discharges air for direction against the hands and face of a user. All devices of this character with which I am familiar have, however, been subject to certain limitations and disadvantages, especially when considered for residence installation, and it is to the overcoming of such disadvantages and limitations that the present invention is directed.

One object of my invention is to provide an 20 electrical hand drier which is compact in design and artistic in appearance.

Another object of my invention is to provide a construction for drying devices of the type under consideration which facilitates an adjustment of 25 the direction of discharge of the heated air.

A further object is to protect the heating unit of the drier from damage upon failure of the blower to operate.

Another object of my invention is to improve 30 the starting characteristics of driving motors of the single-phase induction type.

A still further object is to protect the drier control switch from damage in the event of excess movement of the operating foot treadle.

Another object of my invention is to provide a construction for hand-driers which facilitates a concealment of the floor-fastening means.

An additional object of my invention is to improve the construction of electrical heating units 40 adapted for use in hand driers and other comparable heating devices.

My invention itself, together with additional objects and advantages thereof, will best be understood through the following description of a specific embodiment when taken in conjunction 45 with the accompanying drawings in which:

Figure 1 is a view in side elevation of the improved hand drier of my invention, a portion of the exterior casing being cut away to indicate the internal construction;

Fig. 2 is a view in end elevation of the device of Fig. 1, a portion of the exterior casing also being cut away;

55 Figs. 3, 4 and 5 are section views respectively

taken on lines III—III, IV—IV and V—V of Figs. 1 and 2;

Fig. 6 is a plan view of the improved heating unit which forms a part of the drier shown in the preceding figures;

Fig. 7 is a view in side elevation of the heater of Fig. 6;

Fig. 8 is a side elevational view of one of the resistance-wire supports which forms a part of the heater of Figs. 6 and 7.

Fig. 9 is a view in end elevation of one of the support spacers incorporated in this heater;

Fig. 10 is a view in side elevation of the heater-protecting centrifugal switch which is responsive to the speed of the blower shaft;

Fig. 11 is a view in end elevation of the rotatable composite-ring assemblage which forms a part of the centrifugal switch of Fig. 10;

Fig. 12 is a view in end elevation of the stationary frame and contact carriage comprised by 20 this switch; and,

Fig. 13 is a simplified or schematic diagram showing one preferred manner in which the electrical devices comprised by the improved hand drier of my invention are interconnected with 25 each other for energization from a power circuit.

Referring to the drawings, and particularly to Figs. 1 and 2 thereof, the hand drier of my invention there shown comprises an air blower 10 which is supported in an angle-iron frame comprising four upright members 12, suitably braced and interconnected by cross members certain of which are shown at 14 and 16. Underneath the blower 10, which may be of any one of a number of well-known types now commercially available, 30 is mounted an electric motor 20 which drives the blower by means of an endless belt 22 interconnecting a pulley 21 carried by the motor with a cooperating pulley 24 attached to one end of the blower shaft 112. This particular arrangement 35 of the blower and its driving motor, when of the form and relative proportions shown, has the advantage of reducing the thickness of the complete drier assemblage and, hence, in the interest of compactness of design, is the one which I prefer to utilize.

In the cylindrical air-discharge passage 28 of the blower is positioned an electrical heating unit, the construction of which is more completely 50 shown in Figs. 6 to 9, inclusive. In Figs. 1 and 2 only the protruding top portion 30 of this heater is represented. Operation of the drier is controlled by means of a switch 80, mounted on the angle iron frame work. While, as shown, the 55

switch is actuated by means of a foot treadle 83, it will be understood that, if desired, other actuating means may be used to effect its operation.

Surrounding the draft-producing and air-heating equipment just described is a suitable casing which, as shown, comprises two identical halves 36, preferably constructed of sheet metal, which, as may best be seen by an inspection of Fig. 5, are interconnected by means of metal spacer strips 38 and 39. It will be observed that each edge of the spacing strips 38 and 39 interfits between a flanged portion 48 of the casing member 36 and a soldered-on portion 49 which completes a groove of the proper dimensions and character. This exterior casing completely covers and hence conceals the draft-producing mechanism and in addition forms, above a partition member 40, a pressure chamber or compartment into which the heated air is blown. From this chamber the warm air is discharged for drying purposes through a suitable opening in the top thereof.

It is found preferable to completely assemble the exterior casing before fitting the same down over the blower and driving motor unit to which the two casing halves 36 may be secured by means of screws 44 which fit into threaded holes 45 suitably positioned in certain members of the frame of the blower units. To cover the heads of these attaching screws 44, and to otherwise improve the external appearance of the drier, metal strips 52 are vertically positioned in the manner shown along the centers of the two sides of the casing, they being fitted in a notch 53 at their lower ends and held at their upper ends by the washer or bearing members 54 of the outlet fixture adjuster. To hold the casing halves together during the assembly operation and to further strengthen the complete assemblage at the upper portion thereof, cross braces 46 are provided.

To isolate any vibration which may originate in the hand drier, rubber supports 86 secured to the feet of the blower mechanism framework in the manner shown are provided to effect a resilient contact with the floor or other surface upon which the drier may be set. These supports 86 protrude a short distance below the lower edge of the exterior casing 36 and thereby separate it from direct contact with the supporting surface. While any suitable means for effecting the required air-tight partition between the upper and lower compartments of the blower may be utilized, I have found that a layer of felt represented at 40, the contour of which is such that it intimately contacts the sides of the surrounding casing, in the manner best indicated by Fig. 5, is exceedingly effective. To secure this layer of felt in place, a thin plate of sheet metal 41 may be clamped down over the top of the felt by means of screws 43 which secure it to the structural members of the blower supporting framework therebeneath.

In order that air for discharge through the blower into the upper or pressure compartment may be admitted into the space occupied by the blower structure 10, which draws it through the open spaces in the spoked end bracket 110 of the blower, suitable openings 170 may be made in each end of the lower portion of the casing in the manner shown. During operation of the drier, the air from the room is drawn in through these openings 170, discharged by the blower 10, through the heating coils 90 (Fig. 5) positioned in the outlet 28 of the blower, into the pressure chamber in the upper portion of the casing from

which it escapes through the outlet fixture 42 for direction against the objects to be dried.

The discharge fixture 42 is adjustably mounted to permit the direction of the stream of warm air to be changed by the manipulation of handles 58 which protrude from the pressure chamber sides. When, as illustrated in the drawings, the opening occupies the central or mid-position in its range of adjustment, the heated air will be discharged in a vertical direction from the top of 10 the casing.

The discharge fixture 42 comprises a frame 64 which is supported, through a pair of sheet metal strips 60, from a shaft 56, to the protruding ends of which shaft are attached the adjusting handles 58. These supporting strips may be secured to the shaft by any suitable means such as the pairs of cooperating nuts 62, and have fixed to their upper ends, as by welding, the fixture frame 64. This frame carries a plurality of round bar 20 members 65 arranged in parallel or grille-like fashion over the discharge opening.

In order that the semi-circular path of adjustment travel of the warm-air outlet fixture 42 will be closed with the exception of the area 25 of the fixture, a thin and flexible metal strip 70, shown in Figs. 3 and 4, through an opening in which the frame 64 of the fixture protrudes, is slidably mounted in appropriate slots formed by the raised edges 72 of the opposing top portions of the casing halves 36 and specially flanged metal strips 73 which are welded thereto. It will be understood that if desired the single strip with the opening cut therein may be replaced by two separate strips which are respectively attached to 35 the two ends of the fixture frame 64. As the position of the outlet fixture 42 is changed, the flexible strips 70 will follow in the grooves provided therefor in the semi-circular top section of the casing, and at all times maintain the pressure chamber closed with the exception of the 40 outlet fixture itself.

Manipulation of either of the handles 58 thus causes the outlet fixture 42 to change its position in the semi-circular space between the upper portions of the co-operating casing halves 36 and thereby changes the direction of air discharge. To limit the travel or restrict the range of this adjustment, stop members, in the form of angle pieces 67 welded to the side of the casing, are adapted to make contact with one of the strips 60 when either limit of travel is reached. To prevent chattering of the ends of the flexible strip 70 which protrude below the rim 72 of the casing halves, the welded on strips 73 may be extended down to an intermediate elevation as shown in Fig. 4.

It will be apparent that through the use of this improved construction, adjustment in the position of the outlet fixture 42 may be made with but little effort on the part of the operator, since the friction to movement of the fixture and the flexible sealing strip attached thereto may be reduced to a low value.

Energizing current for the blower driving 65 motor and the air heater is derived through a connection with the lighting or other power supply circuit established by means of a flexible cord 75 terminating in a plug connection 76 which may be inserted into a wall or other outlet fixture. 70 As shown, the cord enters the drier casing through a hole in the bottom of metal strip 38, in which hole an insulating bushing 77 is placed.

The switching device 80, utilized to control the operation of the drier, is illustrated as being of 75

the so-called "momentary contact" type, it completing an energizing circuit only as long as an operating lever 81 thereof, which is maintained in the upward position shown by resilient means 5 incorporated in the switch construction, is continuously depressed. Depression of this lever is effected by means of the foot treadle 83, which protrudes to the outside of the casing through a suitable slot 84 cut in the lower end of the spacer 10 strip 39. Connection between the treadle and switch lever is established by means of a spring 85, which is of sufficient rigidity to transmit switch-actuating movements. The elongating characteristic of the spring allows, without injury to any of the associated mechanism, the treadle to be further depressed after the switch arm 81 has reached its limit of downward travel.

While it will be understood that any suitable air heating unit may be utilized in the hand drier 20 of my invention, the unit which I prefer to utilize because of economy of construction and ease of replacement, is illustrated by Figs. 6 to 9, inclusive, which heater has already been referred to in the explanations of the showings of the complete drier assemblage. One desirable feature of 25 such a heater is that the heating conductors positioned in the passage through which the air to be heated is blown shall be uniformly distributed throughout that passage and shall not unduly obstruct the flow of air therethrough. Thus, it is preferable to position the coils 90 of heating wire in some manner such as is indicated by the showing of Fig. 6 which is a top or plan view of the improved heating unit of my invention which, as 30 before explained, is positioned in the cylindrical outlet passage 28 of the blower 10.

In the construction of this heating unit, a cylindrical shell 30 is formed from sheet metal, a flat strip of which is first cut to the desired dimensions 40 and then bent into the circular contour of the cylinder. In this position the cooperating or overlapping edges of the sheet are spot welded or otherwise secured to each other, this junction being indicated in Fig. 7 by the area of overlap 45 92. In the original flat sheet are also cut two parallel oblique slots 93 and 94, each of which in the assembled cylindrical shell 30 are spiral in form, as also indicated in Fig. 7.

The cylindrical shell having been assembled, 50 porcelain heating wire supports 96, a side view of one of which is shown in Fig. 8, are then inserted in the spiral slots 93 and 94, they being spaced from each other by means of suitably slotted spacers 98 constructed of sheet metal, an end view of one of which spacers is shown in Fig. 9. At the bottom of slot 94 and at the top of slot 93 55 are positioned terminal bolts 97 which secure the two ends of the coil of heater wire 90, which coil is progressively threaded among the specially spaced supports 96 in the manner indicated in Fig. 6. Energizing-circuit connections with the coil are made through the terminals 97 by means of conductors 95, which are threaded through a porcelain bushing 99 carried by a top ring member 100 which surrounds and is secured to the upper portion of the cylindrical shell 30 by an attachment effected by means of bolts 103, to a pair of shell ears 102.

For greater ease in assembly of the heater unit, 70 the coil of heater wire 90 may be threaded through the insulator supports 96 before their insertion into the slots in the cylindrical shell, in which case, this preparatory threading operation may readily be accomplished by arranging the insulators which are to go in each of the two spiral

slots in parallel lines on a flat surface, which lines are spaced substantially by the diameter of the shell, and then threading the coil of heater wire in zig-zag fashion progressively through these supports. When spacedly placed in the two 5 opposing slots, the resulting diversification of the individual branches of the heater coil length shown in Fig. 6 will obtain, and a stream of air in being blown through the cylindrical shell 30 will be uniformly and effectively heated without 10 receiving undue physical obstruction.

In installing the heater unit in the cylindrical discharge opening 28 of the blower 10, it may be secured to the top rim thereof by means of screws 106 which are accommodated by the holes 107 15 in the heater rim 100.

In order to obtain the desired effectiveness of a heater adapted to warm air which is blown rapidly therethrough, it is necessary to operate the resistance wire or conductor at such a high 20 current that should for any reason the draft of air be discontinued, the conductor will attain such excessively high temperatures as to burn out. Consequently, in a device of the type under consideration, should for any reason the blower 25 continue its operation or fail to start upon energization of the heater unit, the unit will be burned out. To protect against damage from this cause is one objective of the present invention.

In effecting such protection, I dispose in the 30 energizing circuit of the heating unit, a centrifugal switch which is responsive to the speed of the blower shaft. This switch, which is generally indicated in the showing of Fig. 1 at 110, requires that the blower 10 be brought up to speed before 35 the heater can be energized and also serves to interrupt the heater circuit as soon as the blower speed decreases to a predetermined low value.

In the improved hand drier of my invention, I prefer to mount this switch directly on the shaft 40 112 of the blower inside of the end bracket 114 in a manner shown in greater detail by Fig. 10. While the switch itself may be of any suitable construction responsive to changes in speed of the shaft, the type which I prefer to utilize is 45 that which is more completely shown and described in United States Patent 1,305,084, which issued May 27, 1919, to John B. Hansell.

As illustrated in Figs. 10, 11 and 12, this switch comprises a composite ring 116, sensitive to 50 changes in the centrifugal force acting thereon, mounted directly upon the blower shaft 112, a base plate 118, attached, by means of screws 120, to the end bracket 114 of the blower, and a carriage 123 mounted in suitable slides on the base 55 plate in a manner to move in a vertical direction therein. This carriage supports, by means of an insulating material bar 126 attached to the lower end thereof, a pair of contact bridging members 124 and 125 which are respectively adapted to 60 selectively make connection with two pairs of stationary contact members 127 and 128 carried on an extension of insulating material 130 which is fixed to the lower end of the base plate 118. Connections with the circuits to be controlled are 65 made by attaching the conductors, as by screws 129, to these stationary contact members.

Changes in the effective diameter of the composite ring 116 effect an actuation of the carriage 70 through the medium of suitable operating lugs 132 and 139 which protrude from the upper portion of the carriage and embrace the ring in the manner indicated by the side view of Fig. 10. The ring comprises, as is best indicated by Fig. 11, 75

a plurality of crescent-shaped movable members 142 symmetrically pivoted, at their ends 145, to a base plate 143 which is directly attached to the shaft 112, each member being biased inwardly by 5 a spring 147. These members 142 nest snugly with each other because of a lateral offset in each of them whereby the pivoted end lies closely adjacent to the base plate 143 and the free end overlies the adjacent member. The free end of 10 each of the members is restrained in movement both inwardly and outwardly by a pin 148 working freely in a slot 150 in the underlying member.

When the ring structure is at rest or revolving at low speeds, the crescent shaped members are 15 all drawn inwardly by the springs 147, as is indicated by the showing of Fig. 11. When sufficient speed is attained by the shaft 112, each of the members 142 flies outwardly under the influence of centrifugal force until stopped by the engagement 20 of the pins 148 with the ends of the slots 150. As the composite ring 116 thus increases in radius, the outer edge impinges upon the upper lug 138 of the contact carriage and pushes it upwardly in a uniform and gradual manner, and conversely, as 25 the composite ring 116 decreases in radius with a decrease in speed, the inner edges of the members 142 contact the lower lug 139 and push the carriage downwardly.

Through the action of a pair of bowed springs 30 132, embraced between a portion 133 of the carriage and extensions 134 of the base member plate, the carriage is biased, in operation of the switch, toward either limit of its movement path so that a quick and positive snap action of the 35 contacts is thereby effected. Thus, when the carriage is in the lower position illustrated, in which stationary contact members 127 are bridged by member 124, the action of these springs is to strongly hold it in that position and thereby 40 maintain the requisite contact pressure. Likewise, when the carriage has been moved upwardly past the midpoint of its movement path, the springs urge it upwardly with a constantly increasing force until it reaches its upper position 45 in which the bridging member 125 is biased against the stationary members 128, the bridging member 124 having by this movement been separated from the stationary members 127.

The total range of movement of the carriage 50 and its actuating lugs 138 and 139 is made to exceed the variation in the radius of speed-responsive ring 116, in order that the crescent shaped members 142 of this ring will not bear upon these lugs at the normal speed of the blower shaft 112, 55 the carriage being allowed to snap free thereof, during each switch actuation, under the influence of bowed springs 132, into its limiting position.

The manner in which the centrifugal switch is 60 connected in the energizing circuit of the heater is most clearly illustrated by the diagram of Fig. 13 from which it will be seen that a depression of the treadle switch 80 first energizes driving motor 20 to start the blower 10. Shortly before the blower attains normal speed, the centrifugal 65 switch actuates the bridging member 125 thereof upwardly to complete an energizing circuit for the heater 90. It will thus be noted that while an opening of the control switch 80 deenergizes both the motor and the heater, upon a closure 70 thereof, heater energization can be effected only while the blower is operating, a failure or discontinuance of such operation immediately causing the centrifugal switch to disconnect the heater from the power source even though the motor 75 may continue to be energized. Effective protec-

tion against burnout due to accidental stoppage or failure of the blower to start is in this manner obtained.

For use with the alternating-current supply circuits which are at the present time almost universal in locations where it is desired to install hand driers and other comparable motor driven devices, single-phase induction motors are especially suitable and it is this type of motor that I have illustrated as being incorporated in 10 the improved hand drier of my invention. In order that such a single phase motor may be started, it is necessary to provide it with an auxiliary winding, shown in the diagrammatic representation of Fig. 13 at 160, physically displaced from the main winding, indicated at 162, which main winding derives its energization directly from the supply conductors 75 through the control switch 80. In order to shift the phase position of the current which is supplied 20 to the auxiliary winding 160, it is necessary to insert in the supply circuit thereof some phase displacing device such as a capacitor 164, and it is preferable that this winding be maintained energized not only during the starting operation 25 but also during the normal full speed running operation of the motor 20.

To increase the rapidity of starting of the motor, it is desirable in situations of this kind to utilize a second or starting capacitor 166 which 30 is connected in the auxiliary winding circuit for a short period after current is first supplied to the motor, the function of this additional capacitor being to increase the current which circulates through the auxiliary winding and thereby substantially raise the starting torque of the motor. To be most effective this increase in current is of such magnitude that damage from sustained overload would result to the auxiliary winding 120 were the starting capacitor to be 40 permanently left in the energizing circuit thereof. In the complete hand drier of my invention shown in Figs. 1 and 2, these capacitors 164 and 166 are shown as being mounted below the motor in the lower portion of the angle-iron frame. 45

To effect a removal of this starting capacitor as soon as the motor has attained full speed, I utilize the second set of contacts comprising bridging member 124 and stationary members 127 of the centrifugal switch, before described as being actuated in accordance with the speed of the driven blower 10. When the motor and blower are at rest, the bridging member 124 completes, as is shown by the diagram of Fig. 13, an active connection of starting capacitor 166 in the circuit through which auxiliary winding 160 of the motor is energized. As soon as the motor and blower come up to speed, however, bridging member 124 is, in the manner already explained, moved upwardly to thereby interrupt the circuit 55 of the starting capacitor to remove it from active service. 60

Although I have shown and described a certain specific embodiment of my invention, I am fully aware that many modifications thereof are possible. My invention, therefore, is not to be restricted except insofar as is necessitated by the prior art and by the scope of the appended claims. 65

I claim as my invention:

1. An electric drying device comprising, in combination, a draft-producing and air-heating mechanism, a structural frame for supporting said mechanism, and an exterior casing adapted to surround said frame and to form thereabove a pressure compartment into which said mechanism 75

- may discharge heated air, said compartment having an opening through which said air may escape for direction against objects to be dried.
2. In an electrical drying device, the combination of a structural frame, an air-blower, a driving motor therefor, and an air heater supported by said frame, an exterior casing adapted to fit down over and be attached to said frame above which the upper portion of the casing forms a 10 chamber, a partition between said chamber and the frame-supported mechanism therebeneath, said partition having an opening through which the heated air is blown into the chamber, and said exterior casing having in the top portion thereof an opening through which said air may escape for direction against objects to be dried.
3. In an electrical drying device comprising a casing in a portion of which is formed a pressure chamber provided with an air-discharge opening of arcuate contour, the combination of an air-outlet fixture, a shaft, the ends of which protrude through the sides of the casing, for adjustably supporting the fixture in said arcuate opening, means for sealing against air escape the 20 portions of said opening not occupied by the fixture, and handles attached to said shaft ends to enable an operator to change the position of the fixture in the casing opening and thereby adjust the directions of air discharge.
- 25 4. In an electrical drying device comprising a casing in a portion of which is formed a pressure chamber provided with an air-discharge opening of arcuate contour, the combination of an air-outlet fixture, a shaft, the ends of which protrude through the sides of the casing, for adjustably supporting the fixture in said arcuate opening, and means for sealing against air escape the 30 portions of said opening not occupied by said

fixture, said means comprising a flexible metal strip through an opening in which the said fixture extends, and grooves provided in the sides of said arcuate casing opening for slidably retaining the edges of said strip.

5. In an electrical heating device comprising an air-blower, a split-phase induction motor, having a pair of windings, for driving the blower, a source of power for the motor, a control switch, a circuit for energizing one of said motor windings directly 10 from the power source upon closure of the switch, a phase-shifting element, and a circuit for energizing the other motor winding through said element upon closure of the switch, the combination of a centrifugal switch, responsive to the speed 15 of the blower, for interrupting said last-named circuit when the blower speed is, during a starting operation, brought up to a value closely approaching normal.

6. In an electrical drying device comprising a 20 heater, a blower for forcing air through said heater, a split-phase induction motor, having a pair of windings, for driving the blower, a source of power for the heater and motor, a control switch, a circuit for energizing one of said motor 25 windings directly from the power source upon closure of the switch, a phase-shifting element, a circuit for energizing the other motor winding through said element upon closure of the switch, and a circuit through which the heater may be 30 energized, the combination of a centrifugal switch, which is responsive to the speed of the blower, adapted to interrupt the motor-energizing circuit last named when the blower speed is brought up to 35 a value closely approaching normal and to, at the same time, complete the said heater energizing circuit.

R. H. JORDAN.
